REMOVABLE CORE LOCK

John P. Andrew, New Rochelle, N. Y., assignor to
The Yale & Towne Manufacturing Company,
Stamford, Conn., a corporation of Connecticut

Application June 7, 1945, Serial No. 598,133

17 Claims. (Cl. 70—369)

1

This invention relates to a type of lock known commercially as a removable core cylinder lock. Locks of this class employ what is termed a removable lock core in which is mounted a controlled key plug. When the core is placed into a lock housing for operating lock mechanism therein, a connection is made between the key plug and the lock mechanism for operation of that lock mechanism by the key plug thereafter. The removable lock core contains, in addition to the key plug, key controlled mechanism for operating a retainer for retaining the removable lock core in the lock housing.

My invention relates more particularly to a retaining mechanism for use with a removable lock core of the class indicated.

In order that the present invention may be better understood and appreciated, it will be well to describe generally certain of the prior art structures over which my invention is an improvement. In one of those structures, the removable lock core contains a key plug formed with a keyway through which a series of tumblers may be set to release the key plug for rotation by a predetermined key known as a change key. A retainer that is formed as part of a sleeve cooperating with the key plug, is housed by the removable lock core and serves to lock that core within a lock housing. When a key other than a change key is inserted into the key plug, it rotates both the key plug and sleeve so as to move the retainer to release position.

In an improved type of structure covered in an application by Theodore H. Johnstone Serial No. 474,806 filed February 5, 1943, now Patent No. 2,391,833, dated December 25, 1945, the removable lock core contains two rotatable tumbler controlled plugs. The tumblers for releasing either one of the plugs for rotation are controlled from a single keyway in but one of the plugs. When the change key is inserted into the plug having the keyway, only the change key plug is rotatable to operate lock mechanism mounted in the housing in which the removable lock core is retained. When a second or retainer controlling key is utilized, the retainer plug is released for rotation. While the Johnstone structure is very effective, those skilled in the art will readily appreciate that the security of the retainer mechanism is dependent on a single series of tumblers set in either of two positions by the change key and the retainer controlling key.

It is one of the objects of the present invention to increase the security of the retainer operating means so as to render more difficult the sur-

2

repetitious removal of the removable lock core from a lock housing in which it may be mounted.

As a feature of my invention I employ in my removable lock core two independently movable key plugs each equipped with a keyway and with one key plug operable by the change key, while the other key plug is operable by the retainer controlling key and is adapted to move the retainer into and out of retaining position.

As a further feature of the invention, the retainer controlling key and the retainer plug can not effect the movement of the retainer to release position unless the change key and change plug are rotated. It is obvious that because of this relationship of the parts, it is necessary for two independent sets of tumblers to be set by two keys before the retainer may be moved to release position.

As a further feature of the invention, the change plug is retained in the removable lock core by a plug retainer detent that is in turn held against movement out of retaining position by part of the lock mechanism in the housing into which the removable lock core is inserted. As still a further feature of this part of the invention, the plug retainer detent is held against movement out of retaining position by pins extending from the lock operating mechanism into bores formed in the change key plug.

It is still a further feature of the invention that the plug retainer detent of the change plug controls the movement of the retainer out of retaining position, preferably by preventing rotation of the retainer plug.

I have thus outlined the more important features of my invention in order that my contribution to the art may be better understood and in order that the relation of my contribution to the prior art may be better comprehended. I do believe that my contribution is a broad and valuable one and that my patent claims should not be limited to the specific structure herein described. Also, while I have described generally several important features of my invention, there are other important features that will be described particularly in the specification and will be claimed in the claims appended hereto.

At this point it will be well to indicate further that I shall describe the removable lock core as mounted in and removable from a padlock casing or housing. Those skilled in the art will fully appreciate that the removable lock core may be used in any type of lock housing such as the usual mortise cylinder or nightlatch cylinder, or

in any other place where a cylinder lock core may be inserted for operating lock mechanism.

Referring now to the drawings, Fig. 1 is an elevation of a padlock in which my invention may be embodied. Fig. 2 is a section of the padlock of Fig. 1 but with the removable lock core removed therefrom. Fig. 3 is an elevation of the removable lock core as it would appear when removed from the padlock housing. Figs. 4 and 5 are sections taken along lines 4-4 of Fig. 2 showing the shackle of the padlock in locked position and in unlocked position. Fig. 6 is a composite section taken along lines 6-6 of Figs. 2 and 3, so as to show the removable lock core within the padlock. Fig. 7 is a view taken along the same lines as Fig. 6 but with the change and retainer plugs rotated to release the removable lock core for movement out of the padlock housing.

Fig. 8 is a plan view of an assembly plate used in my invention. Fig. 9 is a plan view of the rotary bolt used in my padlock and illustrating the relation of a lug of the rollback cam relatively thereto. Fig. 10 is an exploded view of the change plug and the plug retainer detent. Fig. 11 is an exploded view of the rollback cam and the bolt with the bolt spring positioned therebetween. Fig. 12 is a section taken along the lines 12-12 of Fig. 3. Figs. 13 and 14 are front end views of the removable lock core looking upwardly at the bottom of Fig. 3 and showing the two key plugs in the positions of Figs. 6 and 7 respectively.

Referring now more particularly to the drawings, and especially Figs. 1-5 inclusive, my invention is adapted for use within a padlock housing 10 with which cooperates a shackle 11 of the usual type well known in the art. This shackle has a relatively short leg mounted in a bore 12 in the housing 10, and a relatively long leg housed in a bore 13 of the padlock housing 10. A spring 14 tends to move the shackle 11 toward release position but the shackle is restrained against such movement by locking balls 15, 16 and 17. Thus, locking ball 15 is adapted to cooperate with a groove 18 in the long shackle leg while ball 17 cooperates with a groove 19 in the short shackle leg.

For controlling the locking balls 15, 16 and 17, I utilize a rotary bolt 20 having release depressions 21 and 22, which when placed opposite the balls 15, 16 and 17 as shown in Fig. 5, allow release movement of the said balls and out of locking grooves 18 and 19.

A spring 23, best shown in Fig. 11, has an upper end 24 that is adapted to enter a bore 25 in the padlock casing 10 as best illustrated in Fig. 2. The lower end 26 of the spring 23 enters a radial slot 27 of the bolt 20, the spring being so formed that when so positioned, it normally urges the bolt 20 into its locking position of Fig. 4. Directly underneath the flange 28 of the bolt 20 there is mounted a rollback cam 29 as best illustrated in Fig. 2, the cam itself being best shown in Fig. 11. This cam has an integral lug 30 that operates in a slot 31 of the bolt 20 for rotating the bolt from the locking position of Fig. 4 to the release position of Fig. 5. For holding the bolt 20 and the rollback cam 29 in the position of Fig. 2, I utilize an assembly plate 33 best illustrated in Fig. 8. This assembly plate is formed with a pair of slots 34 whereby it may be slipped over pins 35 extending from rollback cam 29, and against the surface 36 of the padlock housing 10. The assembly plate 33 may then be staked into position to maintain the parts assembled as shown in Fig. 2.

Those skilled in the art will fully understand that the rollback cam 29 is rotatable by a suitable key plug through the medium of its pins 35, the slots 34 of the retainer plate 33 being formed to allow such rotation. Through the lug 30, the bolt 20 will be rotated by rollback 29 to allow movement of the locking balls 15 and 16 into depressions 21, 22 as shown in Fig. 5. In that position of the parts, the shackle 11 will spring upwardly under the influence of its spring 14 so as to hold the bolt 20 in its release position. The rollback cam 29 may now be operated back to its normal position because of the relation of the lug 30 to slot 31 of the flange 28 of bolt 20. The purpose of this structure is to allow the removal of the key from the key plug that is used for rotating the rollback cam 29. Thereafter, the downward movement of the shackle 11 will align its locking grooves 18 and 19 with the balls 15 and 17. When this is done, the said balls will move into locking relation to the shackle while the bolt 20 is rotated by spring 23 into its position of Fig. 4 to maintain the balls 15 and 17 in locking position. At this point it will be well to indicate that the rotation of the bolt 20 is best limited by a stud 37 that is inserted into position through the outer wall of the housing 10.

The housing 10 of the padlock is formed with a large opening 38 of cross-sectional form that may best be noted from Figs. 6 and 7. Communicating with this opening 38 is a retainer slot 39, also best shown in Figs. 6 and 7. It is into this opening 38 that the removable lock core of my invention is insertable. At this point it will be well to indicate that the padlock construction I have so far described may be used in cooperation with removable lock cores such as are now known in the prior art and reference to which I have made hereinabove. I shall now describe the detailed structure of the removable lock core of my invention.

Reference numeral 40 indicates generally my removable lock core, over the front end of which is fitted a scalp 41 that may be secured thereto by screws or staking, all as those skilled in the art will appreciate. A change key plug 42, having a keyway 43, is mounted within removable lock core 40 for rotation therein. For controlling the rotation of the change key plug 42 I utilize a standard well known pin tumbler mechanism designated generally by reference letter P and utilizing a series of springs 44, drivers 45 and tumblers 46 mounted in aligned bores formed in the key plug and the lock core.

Mounted also in the lock core 40 is a second key plug designated by reference numeral 47 and called by me the retainer key plug. This retainer key plug is formed with a keyway 48 and is controlled in its rotation relatively to the removable lock core 40 by tumbler mechanism designated by reference letter P'. The tumbler mechanism P' comprises standard pin tumbler mechanism known in the art and embodying here a series of springs 47a, drivers 48 and tumblers 49 mounted in aligned bores that are formed in the plug 47 and the removable lock core 40. Those skilled in the art will readily appreciate that when a change key C is inserted in the keyway 43 as best illustrated in Fig. 12 for setting the tumbler mechanism P, change key plug 42 may be rotated from its position of Fig. 12 to its position of Fig. 14. Similarly, when a retainer key R is inserted into plug 47 to set the tumbler mechanism P', the retainer plug 47 may be rotated from the position of

Fig. 12 to the position of Fig. 14, unless otherwise restrained as I shall presently indicate.

For retaining the removable lock core 40 within the opening 38 of the padlock housing 10, I utilize a retainer 50 best illustrated in Figs. 6 and 7. This retainer 50 is preferably fixed to the upper end of the retainer plug 47, as by screws or other means 51, and is therefore rotatable with the retainer plug 47 from its retaining position of Fig. 6 to its release position of Fig. 7. As is well shown in Fig. 6, a portion of the retainer 50 lies within the retainer slot 39 of the padlock housing 10 and prevents endwise movement of lock core 40 out of the said housing. As shown in Fig. 7, the retainer 50 is completely out of the retainer slot 39, and the removable lock core may be moved out of the opening 38 of padlock housing 10. For limiting the throw of the retainer 50 and the retainer plug 47, a limit lug 52 is secured to the upper end of the removable lock core 40 as best illustrated in Figs. 3 and 7.

Not only does the retainer 50 act to retain the removable lock core 40 within the padlock opening 38, but it also serves to retain the plug 47 against removal from the lock core itself. For similarly preventing removal of the change plug 42 from the removable lock core 40, the change plug 42 is slotted at 53 for cooperation with a plug retainer detent 54. When the plug retainer detent 54 is moved into its full retaining position, a sharp shoulder 55 formed on one of its arms springs into such relation to the body of plug 42, as best illustrated in Figs. 6 and 7, as to yieldingly prevent movement of the retainer detent out of retaining position. Moreover, the pins 35 of the rollback cam 29 are adapted to enter bores 56 of the change plug 42 as well as depressions 57 of the plug retainer detent, and will thereafter function to lock the plug retainer detent 54 from movement out of assembled relation to the key plug 42. This action of the pins 35 takes place whenever the removable lock core 40 is moved upwardly into the housing 38 as from the position occupied thereby relatively to the padlock casing 10 shown in Fig. 3.

The plug retainer detent 54, when the change plug and retainer plug are in their positions of Fig. 6, acts to deadlock the retainer 50 and plug 47 in their lock core retaining position of Fig. 6. This seems rather obvious. It also seems quite apparent that until the proper key is inserted in change plug 42 so as to rotate that plug from its positions of Figs. 6 and 13 to its positions of Figs. 7 and 14, the retainer 50 may not be rotated from its retaining position of Fig. 6 to its release position of Fig. 7. Obviously, once the change plug 42 is rotated to its position of Fig. 7, the retainer plug 47 and retainer 50 may be rotated also to the position of Fig. 7 to allow removal of the removable core 40 outwardly of the opening 38 of the padlock housing 10. It is obvious therefore, that it is necessary to rotate the change plug 42 as well as the retainer plug 47 in order to release the removable lock core 40 for movement out of the padlock casing 10.

When it is desired to insert the removable lock core 40 into the housing 10, both key plugs are placed in their positions of Fig. 7 and the core housing is then moved into the opening 38. Thereafter, the retainer plug 47 is rotated to its position of Figs. 6 and 13 to place the retainer 50 within the retainer slot 39. The change plug 42 is now rotated to bring the plug retainer detent

54 into deadlocking relation to the retainer 50 as shown in Fig. 6. It is interesting to note that even if substantial pressure is applied against the plug retainer detent 54 when the plugs are in their position of Fig. 6, the rollback pins 35 will effectively prevent separation of the plug retainer detent 54 from the change key plug 42.

I now claim:

1. In a lock of the class described, a housing, a lock core removably mounted in said housing, a pair of independently movable key plugs movably mounted in said lock core, tumblers for locking said key plugs against movement in said lock core, and each of said key plugs having a keyway therein whereby said tumblers are key set and said key plugs are released for movement relatively to said lock core, and retaining means movable between a release position and a retaining position for retaining said lock core in said housing and adapted for movement by one of said key plugs out of retaining position and into a release position.

2. In a lock of the class described, a housing, a lock core removably mounted in said housing, a pair of independently movable key plugs movably mounted in said lock core and each having a keyway, an independent set of tumblers extending between each of said plugs and said lock core and adapted for positioning by keys in the keyways of said key plugs to release said key plugs for movement relatively to said lock core, and retaining means movable between a release position and a retaining position for retaining said lock core in said housing and adapted for movement by one of said key plugs out of retaining position and into a release position.

3. In a lock of the class described, a housing, a lock core removably mounted in said housing, a pair of independently movable key plugs movably mounted in said lock core, tumblers for locking said key plugs against movement in said lock core, and each of said key plugs having a keyway therein whereby said tumblers are key set and said key plugs are released for movement relatively to said lock core, retaining means carried by said lock core and movable between a release position and a retaining position for retaining said lock core in said housing, said retaining means being adapted for movement by one of said key plugs out of retaining position and into a release position, and means in said housing movable by movement of the other of said key plugs.

4. In a lock of the class described, a housing, a lock core removably mounted in said housing, a pair of independently movable key plugs movably mounted in said lock core and each having a keyway, an independent set of tumblers extending between each of said plugs and said lock core and adapted for positioning by keys in the keyways of said key plugs to release said key plugs for movement relatively to said lock core, retaining means carried by said lock core and movable between a release position and a retaining position for retaining said lock core in said housing, said retaining means being adapted for movement by one of said key plugs out of retaining position and into a release position, and means in said housing movable by movement of the other of said key plugs.

5. In a lock of the class described, a housing, a lock core removably mounted in an opening formed in said housing, a pair of key plugs rotatable in said lock core on parallel axes and each having a keyway, said lock core having a

series of tumbler bores formed in alignment with bores in one of said key plugs when said key plug is in an initial locked position, said lock core having a second series of tumbler bores formed in alignment with bores in the other of said key plugs when said other key plug is in an initial locked position, tumblers mounted in said bores for positioning by keys inserted into the keyways of said key plugs, and a cam secured on one of said key plugs adapted for rotation therewith into a slot in said housing.

6. In a lock of the class described, a housing, a lock core removably mounted in an opening formed in said housing, a pair of key plugs rotatable in said lock core on parallel axes and each having a keyway, said lock core having a series of tumbler bores formed in alignment with bores in one of said key plugs when said key plug is in an initial locked position, said lock core having a second series of tumbler bores formed in alignment with bores in the other of said key plugs when said other key plug is in an initial locked position, tumblers mounted in said bores for positioning by keys inserted into the keyways of said key plugs, a retainer for locking said lock core in said housing, and means whereby said retainer is movable by one of said key plugs to release said lock core for movement out of said housing.

7. In a lock of the class described, a housing, a lock core removably mounted in an opening formed in said housing, a pair of key plugs rotatable in said lock core on parallel axes and each having a keyway, said lock core having a series of tumbler bores formed in alignment with bores in one of said key plugs when said key plug is in an initial locked position, said lock core having a second series of tumbler bores formed in alignment with bores in the other of said key plugs when said other key plug is in an initial locked position, a retainer for locking said lock core in said housing, means whereby said retainer is movable by one of said key plugs to release said lock core for movement out of said housing, locking mechanism in said housing, and means whereby said locking mechanism is movable by the other of said key plugs.

8. In a lock of the class described, a housing, a lock core removably mounted in said housing, a pair of independently movable key plugs movably mounted in said lock core and each having a keyway therein whereby said key plugs are released by key operation of tumblers for movement relatively to said lock core, means retaining said lock core in said housing adapted for movement by one of said key plugs out of retaining position, and means whereby movement of the other of said key plugs is a requisite to the movement of said retainer out of retaining position.

9. In a lock of the class described, a housing, a lock core removably mounted in said housing, a pair of independently movable key plugs movably mounted in said lock core and each having a keyway, an independent set of tumblers extending between each of said plugs and said lock core and adapted for positioning by keys in the keyways of said key plugs to release said key plugs for movement relatively to said lock core, means retaining said lock core in said housing adapted for movement by one of said key plugs out of retaining position, and means whereby movement of the other of said key plugs is a requisite to the movement of said retainer out of retaining position.

10. In a lock of the class described, a housing,

a lock core removably mounted in said housing, a pair of independently movable key plugs movably mounted in said lock core and each having a keyway therein whereby said key plugs are released by key operation for movement relatively to said lock core, a cam rotatable by one of said key plugs and adapted when in one position to coat with said housing to retain said core within said housing, and means whereby movement of the other of said key plugs is a requisite to the movement of said cam out of retaining position, relatively to said housing.

11. In a lock of the class described, a housing, a lock core removably mounted in said housing, a pair of independently movable key plugs movably mounted in said lock core and each having a key way, an independent set of tumblers extending between each of said plugs and said lock core and adapted for positioning by keys in the keyways of said key plugs to release said key plugs for movement relatively to said lock core, means retaining said lock core in said housing adapted for movement by one of said key plugs out of retaining position, means whereby movement of the other of said key plugs is a requisite to the movement of said retainer out of retaining position, and means in said housing movable by movement of the other of said key plugs.

12. In a lock of the class described, a housing, a lock core removably mounted in an opening formed in said housing, a pair of key plugs rotatable in said lock core and each having a keyway, tumblers adapted for positioning by keys inserted into the keyways of said key plugs to release said key plug for rotation, means whereby the rotation of one of said key plugs is a prerequisite to the rotation of the other of said key plugs, retaining means for retaining said lock core in said housing, and means whereby said other key plug moves said retaining means from a retaining to a release position.

13. In a lock of the class described, a housing, a lock core removably mounted in an opening formed in said housing, a pair of key plugs movable in said lock core and each having a keyway, tumblers adapted for positioning by keys inserted into the keyways of said key plugs to release said key plugs for movement, a retainer for locking said lock core in said housing, means whereby said retainer is movable by one of said key plugs to release said lock core for movement out of said housing, and means whereby the movement of the other of said key plugs is a requisite to the movement of said retainer out of retaining position.

14. In a lock of the class described, a housing, a lock core removably mounted in an opening formed in said housing, a pair of key plugs rotatable in said lock core in parallel axes and each having a keyway, said lock core having a series of tumbler bores formed in alignment with bores in one of said key plugs when said key plug is in an initial locked position, said lock core having a second series of tumbler bores formed in alignment with bores in the other of said key plugs when said other key plug is in an initial locked position, a retainer for locking said lock core in said housing, means whereby said retainer is movable by one of said key plugs to release said lock core for movement out of said housing, locking mechanism in said housing, means whereby said locking mechanism is movable by the other of said key plugs, and means whereby the rotation of the other of said key plugs is a requisite to the movement of said retainer out of retaining position.

to the movement of said retainer out of retaining position.

15. In a lock of the class described, a housing, a lock core mounted in an opening in said housing, a cam rotatable on said housing, a key operated plug rotatable in said lock core, pins extending from said core and adapted to enter bores in said key plug when said lock core is inserted into said housing opening, a retainer detent for retaining said key plug in said lock core, portions of said pins maintaining said detent against movement out of retaining position, a second key operated plug rotatable in said lock core, a retainer for said lock core movable through rotation of said second key plug toward a release position, a part rotatable with said first key plug and co-operable with said means of connection, said part preventing the movement of said retainer to a release position by said second plug until said part is rotated by said first key operated plug.

16. In a lock of the class described, a housing, a lock core mounted in an opening in said housing, a cam rotatable on said housing, a key operated plug rotatable in said lock core, pins extending from said cam and adapted to enter bores in said key plug when said lock core is inserted into said housing opening, a retainer detent for retaining said key plug in said lock core, and portions of said pins maintaining said detent against movement out of retaining position.

17. In a lock of the class described, a housing,

a lock core mounted in an opening in said housing, a cam rotatable on said housing, a key operated plug rotatable in said lock core, pins extending from said core and adapted to enter bores in said key plug when said lock core is inserted into said housing opening, a retainer detent for retaining said key plug in said lock core, portions of said pins maintaining said detent against movement out of retaining position, a second key operated plug rotatable in said lock core, a retainer for said lock core rotatable by said second key plug out of retaining position, and a part of said retainer detent of said first plug preventing rotation of said second plug and retainer until said first plug is rotated.
